UNITED STATES PATENT OFFICE.

CHARLES J. WINEBRAKE, OF NEWARK, NEW JERSEY.

GATE.

Application filed October 22, 1924. Serial No. 745,186.

To all whom it may concern:

Be it known that I, CHARLES J. WINEBRAKE, a citizen of the United States, and a resident of Newark, county of Essex, and State of New Jersey, have invented certain new and useful Improvements in Gates, of which the following is a specification.

This invention relates to an improved gate which is adapted for various situations but 10 is particularly adapted to withstand shocks and jars and to prevent the passage of vehicles and passengers, its use being considered primarily as applicable to ferry boats and draw-bridges although its use is not 15 limited to these situations.

The device is also adapted for operation from a distant point such as the pilot house or from the control station of a bridge and can be at the same time operated from various 20 points such as the deck of a ferry boat adjacent the gate thereby making it possible to reduce the labor now employed in operating the gates of ferry boats.

The invention is also designed to provide 25 a series of gates that are positive and sure in their operation and that will securely hold vehicles from rolling off the ends of boats and through open draws, the gates being preferably operated by fluid pressure 30 such as steam or air although any other means of operation can be provided.

The invention is illustrated in the accompanying drawings in which Figure 1 is 35 a sectional view showing in general outline the hull of a ferry boat, the gates being shown in elevation but one of the operating cylinders being shown in section, this view showing the gates closed, and Figure 2 is a similar view but with the gates shown open.

40 It is customary now to either use a chain or a heavy cable which is caught over hooks at its ends and which extends across the roadway as a bar to the passage of vehicles. The side roadways or openings for foot passengers have at present the ordinary toggle 45 form of gates which are independently operated and which are collapsed against the side of the roadway. The description of roadway means any of the situations or 50 services used for vehicles and to which this form of gate is adapted but in the drawings the roadway is shown as the deck 10 on the hull 11, the deck having standards 12 on each side of the main roadway and which

standards define with the end rails 13 the 55 side roadways for passengers.

The main gate 14 extends between the standards and within the standards so that the gate is held against any side movement but can be moved vertically to cause the 60 ends 15 within the standards to slide in the opening or slot 16 in the standard. Under the roadway is a recess 17, usually a narrow recess, which loosely receives the gate 14 when it descends and in the case of a boat, 65 is usually provided with a drain pipe 18.

On either side of the recess is arranged a cylinder 19 with a piston 20 in it, each of the pistons 20 having a piston rod 21 extending through a stuffing-box 22, the top 70 end of the piston rod 21 being fastened as at 23 by any suitable means to an end 15 of the gate 14. The piston and its movement is controlled by a fluid under pressure, usually air, which can be contained in a reservoir 24 supplied by any suitable pump or compressor (not shown).

The pipe 25 leads from the reservoir 24 to the valve 26 which can be of any of the usual types of three-way valves operated by 80 a handle 27. The valve can be placed as shown in Figure 1 or in the case of a boat, it can be put in a pilot house and operated by an officer in charge of the boat, or it can be placed in the engine room of a bridge when 85 the gate is placed on a bridge, in fact, in any convenient point distant from the gate where a person responsible for the traffic control is located.

The valve 26 can be manipulated to admit 90 the air to the pipe 28 connected to the top of the cylinders 19 and in this way forces the pistons 20, and consequently, the gate 14 down to the position shown in Figure 2. The roadway is now open. When the valve 95 26 is operated to shut this off and to admit compressed air to the pipe 29, this pipe leading into the bottom of the cylinders, it will raise the piston and consequently the gate, as shown in Figure 1. The valve 26, of 100 course, will have the usual venting arrangement whereby the pressure in one pipe is released and the pressure is put on the other.

For the side passages I show the side gates 30 which can be vertically operated but I 105 prefer to make them of the collapsible type with the horizontal arms 31 pivoted as at 32 to the standards and having the pickets

or bars 33 pivotally arranged on the bars 30 so that the gate can be swung upward and collapsed as shown in Figure 2. It will be understood that the limitations of the 5 patent sheet make it impossible to show a complete collapsing against the standards as will be possible in actual construction.

To raise and lower the side gates I provide a connection between them and the 10 main gate so that they all open together and also close together. In the drawings, this connection is in the form of a strand or chain 34 passing over pulleys 35 at the top of the standards and connected as at 36 to 15 the side gates and as at 37 to the main gate.

It will thus be evident that when the main gate is pushed down into the recess 17, it 20 pulls on the chains 34 to raise the gates 30 so that all the gates are thus opened simultaneously. When the gate 14 is pushed up to close it, the gates 30 will descend by gravity and close the side passages.

It will be evident that various changes can be made in the construction shown without departing from the scope of the invention.

I claim:

1. A gate comprising a main gate, a support for the gate above the roadway, the 30 roadway having a recess into which the gate can descend, side gates pivoted on the support and adapted to collapse toward the support when raised, and a connection between the main gate and side gates whereby the lowering of the main gate opens the side gates.

2. A gate comprising a pair of standards projecting above the roadway, a gate slid- 35 able with its ends in the standard, the roadway having a recess to receive the gate, a pressure mechanism under each standard and connected to the sides of the gate to lower and raise the same,

45 3. A gate comprising a pair of standards flanking the roadway, a gate slidable in the standards and adapted to descend in a narrow recess in the roadway, a cylinder under each standard, a piston in each cylinder, a piston rod connected to each piston and 50 supporting the end of the gate within the

standards and a valved supply system for controlling the raising and lowering of the gate.

4. A gate comprising a pair of standards flanking the roadway, a gate slidable in the 55 standards and adapted to descend in a narrow recess in the roadway, a cylinder under each standard, a piston in each cylinder, a piston rod connected to each piston and supporting the end of the gate within the 60 standards, a valved supply system for controlling the raising and lowering of the gate, side gates pivoted to swing inwardly against the standard, and a connection to raise the side gates when the main gate is 65 lowered.

5. A gate comprising a pair of standards flanking the roadway, a gate slidable in the standards and adapted to descend in a narrow recess in the roadway, a cylinder under 70 each standard, a piston in each cylinder, a piston rod connected to each piston and supporting the end of the gate within the standards, a valved supply system for controlling the raising and lowering of 75 the gate, side gates pivoted to swing inwardly against the standard, and a strand passing over each standard with its ends secured to the main gate and the side gate on that side whereby the gates are opened and 80 closed simultaneously.

6. A gate for ferry-boats and the like comprising the combination of the deck having a vertical narrow recess therein with a pair of standards and having a sliding gate with its ends in the standards, side gates hinged to the outer sides of the standards, a strand passing over each standard and connecting the gates so that when the centre gate is moved vertically the side 85 gates are moved in the opposite direction, a cylinder under each standard, a piston rod emerging from each cylinder and secured to an end of the sliding gate, and a valved system for supplying compressed fluid to the cylinders to operate the sliding gate.

In testimony that I claim the foregoing, I have hereto set my hand, this 18th day of October, 1924.

CHARLES J. WINEBRAKE.
